UNITED STATES PATENT OFFICE.

WILLIS MCKEE, OF CLEVELAND, OHIO, ASSIGNOR TO CENTRAL NATIONAL BANK OF CLEVELAND.

CONVEYER.

Application filed October 16, 1923. Serial No. 668,890.

This invention relates to conveyers for intermittently transporting elongated material thereacross. More particularly, my invention relates to conveyers of the type employed in hot beds which form the subject matter of U. S. Letters Patent, No. 1,486,984, issued to me on March 18, 1924, wherein I have pointed out some of the problems which are incident to the design of such structures.

In my former application I transport the hot material across the bed by using two sets of supporting members, and provide mechanism which will cause one of the sets to reciprocate synchronously vertically and horizontally, thereby moving such set of members in an elliptical orbit, relative to the other set of members during each upper travel of which set of members, the material is transported across the bed, a distance equal to the horizontal axis of the elliptical orbit travelled thereby. This mechanism can be adjusted to cause the movable set of members to travel a definite distance in a forward or rearward direction, while in a plane above the other set of members, or to travel in a vertical plane without any horizontal movement. There are times when I find that it is desirable to regulate the length of the above described forward or rearward travel of the movable members, such being the case when rolling mills feed material at varying speeds, when wide ranges of material are fed from the rolling mill, and when it is desired to increase the capacity of a given bed to handle a larger volume of material.

An object of my invention is to provide mechanism which can be readily adjusted to definitely regulate the length of the horizontal axes of the elliptical orbit in which a set of supporting members is moved.

Another object of my invention is to provide mechanism which can be readily adjusted to definitely control the length of the horizontal axis of the elliptical orbit in which a movable set of supporting members will travel, when moving in either a forward or rearward direction while above the level of the other set of supporting members.

Another object of my invention is to provide a simple mechanism for moving a set of work supporting members continuously in an elliptical orbit, and in providing hand operated adjusting means associated therewith

for definitely controlling and regulating the length of the horizontal axes of the elliptical orbits in which the supporting members are moved.

Another object of my invention resides in providing mechanism to synchronously reciprocate one set of work supporting members vertically and horizontally, the mechanism including a Stephenson link which can be adjusted so that the movement of the set of members may be readily varied to transport material across the bed in either a forward, or rearward direction, or to reciprocate the material vertically without any horizontal movement, the movement of the members being also controlled by the adjustment of the Stephenson link, to definitely determine the distance the material is intermittently moved across the bed.

It will be understood that the term "Stephenson link" as used in this specification has been used not in a limiting sense, but as descriptive of movements suitable to the present invention, the Stephenson link and the movements obtainable therefrom being well known in the art.

Another object of my invention is to divide a movable set of work supporting members into two transverse sections which are movable separately, and which are connected so that they counterbalance each other.

Another object of my invention resides in the provision of mechanism for moving each section of a two part work supporting set of members in separate elliptical orbits, the horizontal axes of which are of different lengths and are adjustable in such relation, whereby the material being moved across one part of the bed will progress at a slower rate of speed than that on the other part, and the rate at which the material travels on each part of the bed can be definitely regulated.

These and other objects, and the invention itself will appear in the following specification, and in the accompanying drawing wherein:

Figure 1 illustrates a plan view of a hot bed, partially broken away, embodying my invention.

Figure 2 is a side elevation of the same illustrating the mechanism for vertically reciprocating the movable set of supporting members taken on line 2-2 of Fig. 1.

Figure 3 is a fragmentary side elevation

of mechanism including a Stephenson link for reciprocating the movable set of supporting members horizontally, taken on line 3—3 of Fig. 1.

5 Figure 4 is a fragmentary section taken on line 4—4 of Fig. 1, illustrating the hand lever and locking means for operating and setting the Stephenson link.

10 Figure 5 is a fragmentary section taken on line 5—5 of Fig. 3 illustrating the details of the Stephenson link.

15 Figure 6 is a top plan view of modified form of hot bed wherein the movable set of supporting members is shown in two connected parts.

20 Figure 7 is a sectional view of the same taken on line 7—7 of Fig. 6 showing the mechanism for reciprocating the parts vertically.

25 Figure 8 is a fragmentary section taken on line 8—8 of Fig. 6 illustrating the Stephenson link for reciprocating the parts horizontally.

30 Figure 9 is a fragmentary section taken on line 9—9 of Fig. 6 illustrating the counter-balancing connection between the two parts of the movable set of members.

35 Figure 10 is a fragmentary view of an adjustable counterbalancing arm, and

40 Fig. 11 is a section taken on line 11—11 of Fig. 1 illustrating the support for the stationary members and the manner in which the movable members are supported therebetween.

45 Referring to the drawings by characters of reference, 15 represents a plurality of supporting members having spaced upstanding supporting arms 16. The arms are arranged in alignment in longitudinal rows

50 and stationary work supporting members 17 are supported upon and secured to the upper aligned ends thereof. The stationary supporting members are spaced in parallel relation, and are termed herein as a stationary set of supporting members, although they also can be made to move so the movement of the material across the bed will be continuous if so desired. Movable work supporting members 18, are arranged to ex-

55 tend longitudinally between the spaced stationary members, and are rigidly united integral together, as a set, by transversely extending I-beams 19, to which they are fastened in any suitable manner. It will thus be seen that the hot bed comprises alternate stationary and movable members which extend longitudinally, each group of which are termed a set of members. The movable set of members are of greater vertical thickness than the stationary members, and are movable between the arms 16 supporting the stationary members.

60 A plurality of supporting brackets 20 are secured to the foundation, intermediate adjacent standards, and are positioned in

alignment near the ends of the bed, or at a plurality of points if the bed is of great length. These brackets are provided, in Figures 1 and 2, with bifurcated upper ends, between which the angular portions of bell 70 crank levers 21 are pivotally secured at 22. The horizontally extending arms of the bell crank levers project substantially beneath the I-beams 19, and are connected thereto by links 23 which are pivoted at 24 to brackets 75 projecting from the beams 19, and at 25 to the ends of the horizontal arms of the bell cranks. The levers 21 and the links 23 provide pivoted supports for the movable set of work supporting members 18, 80 through the connecting beams 19.

85 The stationary work supporting members and the alternately positioned movable work supporting members, together with their supports, are termed a hot bed. The hot metal bars as they come from the rolling mill, are deposited transversely across the supporting members at one end of the bed and are fed intermittently across the bed by the movement of the movable set of members, during which transposition the bars become cooled.

90 Adjacent the end of the bed which receives the hot bars, as they come from the rolling mill, is positioned a motor 26 which is supported upon a suitable base, and a shaft 27 to which is keyed a worm 28 is driven thereby. A casing 29 encloses worm 28 and supports a shaft 30 upon which is fixed a worm gear 31 and a gear 32, the worm gear 31 meshing with worm 28. A gear 33 is fixed to shaft 34, and all of the gears are enclosed by the casing 29, the shaft 34 extending through the casing and being rotatably mounted in bearings therein. This shaft 34 which is rotated by the motor, through gearing within the casing, is also rotatably supported by spaced brackets 35 in suitable bearings 36 intermediate its length. The shaft 34 extends substantially the length 105 of the head, or receiving end of the hot bed and is the medium by which the movable set of work supporting members are moved.

110 Members 37 are fixed eccentrically to the driven shaft 34, adjacent the bracket supports 35, and a two part yoke 38 is mounted around each eccentric member, so that when the shaft is rotated the eccentric members will rotate within the yokes thereby reciprocating the yokes horizontally during each 115 rotation. Rods, composed of sections 39 united by turnuckles 40 screwed on to the adjacent ends thereof, extend longitudinally beneath the supporting members and are pivotally connected at 41 to the upper ends 120 of the aligned bell crank levers 21. The ends of the rods are fixed to the yoke collars 38, and the rods extend between the bed supports 16 and through vertical slots 42 formed in the transverse beams 19. The 125 130

rotation of the members mounted eccentrically upon the shaft 34 causes the yokes 38 and the rods 39 to reciprocate in a horizontal direction, which rods in turn rock the bell crank levers 21 upon their pivots 22 causing the links 23 to vertically reciprocate the beams 19 and the supporting members carried thereby.

A pair of members 43 and 44 are fixed eccentrically to the shaft 34, adjacent the gear 33 and just outside of the casing 29. These eccentrically mounted members are arranged side by side and are encircled by two part bearing yokes 45 and 46 respectively, within which they rotate. Arms 47 and 48 extend relatively radially from the yokes 45 and 46 respectively, and are formed integrally with one part thereof, the eccentric members being mounted at 180° to each other in offset relation upon the shaft to cause the radial relation of the arms. The ends of the arms are pivotally connected to opposite ends of an arcuate member 49, which has an arcuate slot 50 therein. A bearing block 51 is slidably mounted in the slot 50 and a bifurcated end 52, of a rod 53, is pivotally attached to the block 51. Such structure is well known as a Stephenson link connection. The lower end of the arcuate member is hinged by a link 54 to one end of a lever 55, which has a weight 56 secured at the opposite end thereof. This lever is fixed to a shaft 57 which is rotatably mounted in bearings in the supports 35, in a plane below the shaft 34. A hand lever 58 is fixed to shaft 57 and by moving the hand lever up or down, the member 49 of the Stephenson link is moved likewise through the lever 55 and the link 54. When the member 50 is in desired position the hand lever can be locked by a pin, or other suitable means to the guard bracket 59. The counter weight lessens the effort required by the operator to move the hand lever.

The rod 53 is pivotally connected at 60 to the front transverse beam 19 forming a part of the movable set of members, and a support 61 is provided intermediate the beam 19 and the Stephenson joint, having a bearing 62 pivoted thereto at 63, the shaft 53 being slidably mounted through the bearing 62. Under the well known principle of the Stephenson link, the rod 53 is reciprocated horizontally when the block 51 is positioned on either side of the center of the slot 50, and when the block is positioned centrally of the ends of the slot the rod 53 will stand still, although the driving mechanism is still operating, and the moving set of supporting members continue to move vertically.

The Stephenson link connection reciprocating the movable set of members horizontally, and the rods 39 reciprocating the movable set of members vertically are both operated by yokes mounted eccentrically upon the

shaft 34, thereby operating synchronously, causing the movable set of members to move in an elliptical orbit. The supports for the movable set of members are so arranged that the movable set of members will be extended in a plane above the stationary members during a portion of their movement, and will lie in a plane below the stationary members during the remainder of the movement. The eccentrics 37 and 43 are so arranged that when a movable set of members has reached the end of its travel in a horizontal direction, the set of members is in the center of its travel in a vertical direction and vice versa. As the movable set of members rises from the level of the stationary set of members, they will elevate the material from the stationary members and transport it the length of the horizontal axis of their elliptical movement, whereupon the material is again deposited upon and supported by the stationary members until the movable members complete their lower elliptical movement and again raise the material, repeating the operations until the material is in desired position upon the bed.

The vertical reciprocation of the movable set of members is continuous while the driven shaft is rotating, but the Stephenson link permits the travel of the movable members above the stationary members to be in either a forward or rearward direction and the lower travel vice versa, when the block 51 is adjusted on either one or the other side of the middle of the member 49. When the block 51 is placed midway of the ends of the slot, the movable member will not reciprocate longitudinally, and will reciprocate vertically only, in which manner the material on the bed will not progress longitudinally but will be raised and lowered by the movable members. The degree to which the block 51 is moved in the slot 50 between the center and the ends will definitely determine the length of the longitudinal reciprocation of the movable set of members when traveling in either a forward or reverse direction above the stationary members, and consequently the nearer the block is to the center of the slot 50, the shorter will be the longitudinal axis of the elliptical orbit travelled thereby. It will be seen that the hand lever 58 which is moved up or down to regulate the position of the member 49 relative to the block 51, can be operated and the adjustment made while the mechanism is in motion, thereby permitting the operator to regulate the direction in which the material is moved on the hot bed, and the length of such movement, and permitting him to arrest the longitudinal movement entirely. If desired a motor may be provided to throw the Stephenson link to adjust the same. It is well known that the speed at which a given mill rolls a given product varies greatly and also that

different products on a given mill occupy greatly different space; these facts make this regulation very desirable.

The positive control and regulation of the longitudinal movement of the movable set of members, will permit a maximum amount of material to be transported in a given space, will keep material straight because of the shifting supports which prevents sagging and bending of the material therebetween, will allow the pieces of material to be spaced as desired, or banked together for annealing, and will permit a wide range of different materials to be handled. The apparatus is easily repaired, can be constructed cheaply, and is of simple construction for the class of work it performs.

In Figs. 7 to 10 inclusive, I have illustrated a modified form of the hot bed, where the movable set of work supporting members are divided transversely in two sections. When rails or similar hot bars are fed onto the bed from the rolling mill, they are cambered, and as they cool while being moved across the hot bed they become cambered in the opposite direction after which they become straight. The degree of camber becomes less as the material is transported toward the delivery end of the bed and I find that in this class of work it is desirable to move the movable set of members so that the delivery section of the movable member will have less horizontal movement than the receiving end, permitting the material to be spaced closer together on the delivery end, and thereby increasing the capacity of the bed. The movable sections of supporting members are heavy and I mount, and connect the sections, so that they substantially counterbalance each other.

In this modified form of bed the driven shaft 34 is located transversely beneath the bed and is driven and supported in substantially the same manner as in the previously described embodiment of my invention. The stationary work supporting members and their supports are the same in both embodiments. The movable work supporting members are located in the same relation as previously described, but are divided transversely in two sections, the ends of which overlap to provide continuous members, and are arranged so that they can move relative to each other. Each of the transverse sections of the movable set of members is connected by a pair of transversely extending beams 19 and is secured thereon. The supports 20 in this instance are located in the same manner as previously described, but are provided with fulcrums 70 upon which the bell crank levers 21 are pivotally supported. Similar fulcrums 71 are provided upon the ends of the horizontal arms of the bell crank levers, and the beams 19 are also provided with fulcrums 72. The links 23

extend between the fulcrums 71 and 72 and support the sections of the movable set of members for similar movement as hereinbefore described.

A member 74 is eccentrically secured upon the shaft 34 and is rotatably mounted in the yoke 75. Rods 76 extend from each side of this collar and are pivotally connected to adjacent bell crank levers supporting the two sets. The bell crank levers supporting each section of movable members are connected by rods 39 in the same manner as previously described. The rotation of the eccentric member will rock the bell crank levers which in turn vertically reciprocate the sections of the movable set of members, the arrangement being such that as one section is moved up, the other section moves down.

The Stephenson link connection is associated with the movable set of members and the shaft 34 in the same manner as previously described, and is also adjusted in the same manner, the shaft 57 being in a plane beneath the shaft 34.

Angular links 77 are pivoted at 78 to adjacent beams 19 of the two sections of movable members and are adjustably secured to one arm of the bell crank levers 79. Supporting brackets 80 are positioned adjacent each other and the bell crank levers 79 are pivoted thereto, the bell crank levers being provided with gear segments 81 which mesh when assembled. This connection between the two sections of the movable set of members causes one to counterbalance the other and provides a connection whereby the movement of one will at all times correspondingly move the other at the same relative ratio, thus when the Stephenson link reciprocates one of the sections the other section will also be reciprocated. The gear arrangement is such, however, as to cause a shorter horizontal reciprocation of the section at the delivery end of the bed, than that at the receiving end thereof.

With this arrangement, the two sections are moved in separate elliptical orbits, the horizontal axis of the orbit in which the delivery section travels being shorter than that of the receiving section, but always being a percentage of the travel of the receiving end. The relative movement of the two sections is such that when one section is rising it is preferable that the other section will be dropping so that the two sections can counterbalance each other; and while one section is traveling forward the other section will be traveling in the opposite direction. Variation in the effective length of levers 79, as by securing lever 77 thereto in various positions as shown in Figs. 9 and 10, results in varying correspondingly the relative horizontal movements of the sections.

In this modified structure the Stephenson link will function to control the movements

of each of the two sections of the set of movable members, just as it did with the single set previously described, the connection with one causing the other to function through 5 the geared connection.

The term Stephenson link connection or motion as employed in the specification and claims herein is intended to include the well known apparatus commonly called a Stephenson link or connection and any and all other apparatus operating in substantially the same manner or accomplishing substantially the same result as the Stephenson link.

Various changes in the details of construction described can be made without departing from the spirit of my invention and the scope of the claims.

What I claim is:—

1. A conveyer comprising two sets of work supporting members, mechanism for intermittently moving one of said sets of members longitudinally in a curving course above the other of said sets of members, and means operable during movement of the movable 25 members for adjusting said mechanism to vary the length of the movement of said set of members.

2. A conveyer comprising two sets of work supporting members, adjustable mechanism 30 for intermittently moving one of said sets of members in either a forward or rearward direction above the other of said sets of members, and means for regulating said mechanism to definitely adjust the length of 35 movement of said set of members in either direction while in operation.

3. A hot bed comprising two sets of work supporting members, one of said sets of members being movable relative to the other, means for imparting vertical reciprocating movement to said movable set of members, and means for synchronously imparting horizontal reciprocating movement to said movable set of members, said last 45 mentioned means being adjustable during movement of the movable members for definitely regulating the length of the horizontal movement of said movable set of members.

4. A hot bed comprising two sets of work supporting members, one of said sets of members being movable relative to the other, means for imparting vertical reciprocating movement to said movable set of members,

means for imparting horizontal reciprocating movement to said movable set of members during the vertical movement thereof, and means movable during the movement of the movable members for adjusting said last 60 mentioned means to vary the length of the horizontal movement of said movable set of members.

5. In a hot bed having a stationary set of work supporting members, and a movable set of work supporting members, the com-

bination of means for imparting vertical reciprocating movement to said movable set of members, and a Stephenson link connection for imparting a variable horizontal reciprocating movement to said movable set of members synchronously with the vertical reciprocation thereof.

6. A hot bed comprising a plurality of work supporting members, one of which sets of members is movable relative to the other, 75 and means for imparting elliptical movement to said movable set of members, said set of members travelling above the other set during a portion of its elliptical movement, said means being adjustable during 80 movement of the movable members to vary the horizontal movement of said movable member.

7. In a hot bed upon which linear materials are placed side by side and caused to 85 progress from the receiving side to the delivery side thereof, alternate stationary and movable members secured together in sets and adapted to support said linear material, and means to impart elliptical movement to 90 said set of movable members, said movable members travelling in a plane above said stationary members during a portion of their elliptical movement to intermittently progress said linear material, said means including adjustable mechanism movable during movement of the movable members for varying the length of the horizontal elliptical movement of said movable members to 95 vary the speed at which said material is moved and the quantity of material which can be handled by said bed.

8. A hot bed comprising a plurality of sets of work supporting members, and means for moving one of said sets of members in 100 an elliptical orbit, a portion of which movement is in a plane above the other of said sets of members, said means being adjustable during movement of the movable members to vary the length of the horizontal axis of 105 the elliptical orbit in which said set of members is moved.

9. A hot bed comprising a pair of sets of work supporting members, means for moving one of said sets of members in an elliptical orbit, said means being adjustable while in motion to vary the amplitude of the horizontal axis of the elliptical orbit in which 110 said set of members is moved.

10. A hot bed comprising a pair of sets of work supporting members, and means for moving one of said sets of members in an elliptical orbit relative to the other, said means being adjustable during movement of the movable members to definitely regulate 115 the length of the horizontal axis of each elliptical orbit in which said set of members is moved.

11. A hot bed comprising two sets of work supporting members, and driving means in- 120

- cluding a Stephenson link connection for moving one of said sets of members in an elliptical orbit relative to the other of said sets of members, said Stephenson link connection being used to definitely regulate the length of the horizontal axis of the elliptical orbit travelled by said members and to reverse the direction of the travel of said member.
- 10 12. A hot bed comprising two sets of work supporting members, and driving means including a Stephenson link connected to one of said sets of members, said link being adjustable to selectively cause said members with which it is connected to either move vertically or in an elliptical orbit, the length of the horizontal axis of the elliptical orbit, and the direction travelled by said members being controlled by the adjustment 15 of said link.
- 15 13. A hot bed comprising two sets of work supporting members, one of said sets comprising a plurality of sections movable relative to each other and to the other set 20 of members, and means for moving each of the plurality of sections in separate elliptical orbits of different lengths.
- 20 14. A hot bed comprising two sets of work supporting members, one of said sets 25 being divided transversely into a plurality of movable sections, counterbalancing mechanism connecting said adjoining sections, means for moving each of said sections in an elliptical orbit, and means movable during movement of the said movable members 30 for changing the horizontal lengths of the said orbits.
- 25 15. A hot bed comprising a set of stationary work supporting members, a set of movable work supporting members, said movable set of members being transversely divided into integral sections, said sections 35 being connected and mounted to counterbalance each other, means for moving said parts of said movable set of members in elliptical orbits of a relatively constant ratio, and means movable during movement of the said movable members for changing the horizontal lengths of the said orbits.
- 35 16. A hot bed comprising two sets of work supporting members being formed as two aligned connected sections, mechanism for moving each of said sections in separate elliptical orbits the horizontal axes of which 40 are different, and means for adjusting said mechanism to definitely control the length of the axes of the elliptical orbits in which said parts are moved.
- 40 17. A hot bed comprising a set of stationary work supporting members, a movable set of work supporting members divided into two aligned sections, a pair of intermeshing gear segments connecting said divided sections, and means for moving said 45 parts in separate elliptical orbits, said di-
- vided parts being mounted to counterbalance each other and to travel in a fixed ratio one to the other.
- 45 18. A hot bed comprising a set of stationary work supporting members, a movable set of work supporting members divided into two aligned sections, mechanism for moving each of said sections in separate elliptical orbits of a fixed relative ratio, said mechanism being adjustable to vary the longitudinal travel of said sections.
- 50 19. A hot bed comprising work supporting members, mechanism for intermittently moving material across said bed, and means for regulating the distance of the intermittent movements of the material while the moving mechanism is in motion.
- 50 20. A hot bed comprising sets of work supporting members, one of said sets of members being movable relative to the other, mechanism for imparting elliptical movement to said movable set of members, and means operable while the moving members are in motion for changing the horizontal axis of said elliptical movement from a maximum length to any other length less than the maximum length.
- 55 21. A hot bed comprising work supporting members, mechanism for moving material intermittently in semi-elliptical orbits across said bed, and means operable while the moving members are in motion for varying the length of the horizontal axis of the semi-elliptical orbits in which the material is moved.
- 60 22. A hot bed comprising sets of work supporting members, mechanism for moving one set of members in a semi-elliptical orbit above the other members, and means operable while the moving members are in motion for regulating the horizontal axis of the semi-elliptical orbit in which said member is moved.
- 65 23. A hot bed comprising a plurality of work supporting members arranged in sets, one of said sets being divided into connected sections, mechanism for moving each of said sections intermittently in separate semi-elliptical orbits above the other members, the motion of one section above the other members terminating as the motion of the adjacent section above the other members begins, and means movable during the movement of the said sections for changing the lengths of horizontal movement of the said sections above the supporting members.
- 70 24. In a conveyer, stationary elements for supporting material, sections of elliptically movable elements arranged longitudinally for intermittently carrying the material longitudinally along said stationary elements, the distances the material is intermittently carried by one of said movable sections being a predetermined percentage of the distances the material is carried by the other

- movable sections, and means operable during movement of the movable members for changing the horizontal distances of intermittent travel of the material.
- 5 25. A hot bed including a plurality of longitudinally arranged sets of cooperating movable and stationary elements, said movable elements carrying material intermittently predetermined distances lengthwise
- 10 across the bed, and means for regulating the operation of both movable sets of elements to cause them to carry the material relatively different distances which are a predetermined percentage of each other.
- 15 26. A conveyer comprising a stationary member, and continuously moving means for intermittently advancing work blanks simultaneously and at two different rates of speed along the stationary member, drive
- 20 means movable at a given speed for actuating the said moving means, and means independent of the drive means for changing the rates of speed of movement of work blanks along the stationary members.
- 25 27. A conveyer comprising a stationary member, continuously moving means for intermittently advancing work blanks simultaneously and at two different rates of speed along the stationary member, drive means
- 30 for actuating the said moving means, and means independent of the drive means for varying the rates of speed of movement of the work blanks without altering the original ratio between the said rates of speed
- 35 thereof.
28. A conveyer comprising in combination stationary members for supporting work blanks, and means, including movable members disposed in a plane or planes parallel
- 40 to the tops of the said stationary members for intermittently carrying work blanks along different parts of the stationary members through different distances of actual travel of the work blanks in the same time
- 45 intervals of actual travel thereof.
29. A conveyer comprising in combination, stationary members for supporting work blanks, movable members disposed in a plane or planes parallel to the tops of the
- 50 stationary members for carrying work blanks along the stationary members in intermittent steps and a power device for actuating the movable members through a cycle at a given speed, the movable members
- 55 cooperating with the stationary members in such a manner that the work blanks travel at a certain speed along a given part of the stationary members which part is greater in length than the distance travelled by the
- blanks in any single intermittent step, and at another speed along another similar part of the said stationary members.
30. A conveyer comprising in combination stationary members for supporting work blanks, movable members for intermittently carrying work blanks along the stationary members, and a power device for actuating the movable members through a cycle in a given time, the movable members cooperating with the stationary members to carry work blanks along different parts of the stationary members through different distances of actual travel of the work blanks in a given cycle of the movable members.
31. A hot bed comprising fixed and movable supports, the movable supports being divided transversely of the hot bed into a plurality of sections, means for imparting elliptical movement to the two sections adjacent to each other, the horizontal axis of which movement is substantially parallel with the top surfaces of the fixed supports, means for varying the amplitude of movement of the said sections above the fixed supports, and means operable during the movement of the movable supports for changing the lengths of horizontal movement of the said movable sections.
32. A conveyer including two sets of work supporting members, one of the said sets being movable, a drive shaft for actuating the said movable set of members, and means independent of the said drive shaft for changing the horizontal length of movement of the set of movable members and reversing the direction of movement of the said set of movable members.
33. In a conveying mechanism, the combination of a frame, bars sustained fixedly relatively to the frame to support the articles to be conveyed, two sets of movable bars associated with the fixed bars to advance the articles thereon and supported from said frame to move up and down and horizontally endwise, operating means for said movable bars, connections between said operating means and the two sets of movable bars formed to move them up and down, and connections between the operating means and the respective sets of bars formed to move the two relatively different distances horizontally, said two movements being coordinated with each other to cause the bars to move in orbital paths.
- In testimony whereof I hereunto affix my signature this 11th day of October, 1923.

WILLIS MCKEE.
